UNITED STATES PATENT OFFICE

ALBERT E. R. SPEIDEL, OF EDGEWOOD, RHODE ISLAND

DESIGN FOR A COMBINED BRACELET CHAIN AND END HOOK

Application filed July 28, 1930. Serial No. 36,493. Term of patent 3½ years.

To all whom it may concern:

Be it known that I, ALBERT E. R. SPEIDEL, a citizen of the United States of America, residing in Edgewood, county of Providence, State of Rhode Island, have invented a new, original, and ornamental Design for a Combined Bracelet Chain and End Hook, of which the following is a specification, reference being had to the accompanying drawing, forming a part thereof.

Fig. 1 is a top plan view; Fig. 2 is a side

elevation; Fig. 3 is a perspective view of the end hook shown in Figs. 1 and 2 and Fig. 4 is a perspective view of the connecting link shown in Figs. 1 and 2 of a combined bracelet chain and end hook, showing my new design.

I claim:

The ornamental design for a combined bracelet chain and end hook, substantially as shown.

ALBERT E. R. SPEIDEL.
